CLAIM

The ornamental design for an absorbent article package, as shown and described.

DESCRIPTION

FIG. 1 is a front, top, and right side perspective view of an absorbent article package, showing our new design;

FIG. 2 is a front elevation view of the absorbent article package of FIG. 1;

FIG. 3 is a view of the right side of the absorbent article package of FIG. 1;

FIG. 4 is a view of the back side of the absorbent article package of FIG. 1;

FIG. 5 is a view of the left side of the absorbent article package of FIG. 1;

FIG. 6 is a view of the top side of the absorbent article package of FIGS. 1; and,

FIG. 7 is a view of the bottom side of the absorbent article package of FIG. 1.

The gray scale shading indicates a contrast in surface appearance.

(Continued)

The evenly broken lines are shown for the purpose of illustrating parts of the article that form no part of the claim. The dot-dash lines represent the boundaries of the claim and form no part thereof.

1 Claim, 6 Drawing Sheets
